UNITED STATES PATENT OFFICE.

LONGLEY LEWIS SAGENDORPH, OF CINCINNATI, OHIO.

DESIGN FOR A METALLIC ROOFING-PLATE.

SPECIFICATION forming part of Design No. 19,139, dated June 4, 1889.

Application filed April 29, 1889. Serial No. 309,054. Term of patent 14 years.

To all whom it may concern:

Be it known that I, LONGLEY LEWIS SAGENDORPH, a citizen of the United States, residing at Cincinnati, in the county of Hamilton, State of Ohio, have invented and produced a new and original Design for Roofing-Plates, of which the following is a specification, reference being had to the accompanying drawings, forming a part thereof.

10 My design consists of a metallic roofing-plate having a succession of irregular depressions or offsets crosswise of the plate, and in such a manner that the lowest points of each depression or offset will come directly over the highest point of the next lower depression, a vertical grooved depression being formed in the plate, which gradually tapers in depth from the highest point in each cross-depression to the lowest point of the cross-depression immediately above, said cross-depressions and vertical grooves forming a raised block or figure of irregular configuration.

15 In the drawings, wherein Figure 1 shows a plan and Fig. 2 a side elevation of my design, the first two depressions or offsets A A across the top of the plate are of a wave-like or corrugated form—that is, the offset along this line tapers from the point *a* to the point *a'*, as shown in Fig. 2. The two succeeding depressions or offsets B B are of a zigzag form across the sheet and taper from the point *b* to the point *b'*, as shown in Fig. 2. The two succeeding depressions or offsets C C are of an escaloped form across the sheet, and are tapered along these lines from the point *c* to the point *c'*, as shown in Fig. 2. The two

succeeding and the last depressions or offsets D D across the sheet are of a triad form and taper along this line from the point *d* to the point *d'*, as shown in Fig. 2. A groove E extends from the lowest point of each of the cross depressions or offsets to the highest point of the succeeding lower depression or offset, said groove gradually tapering in depth from said highest point to said lowest point.

20 It will be seen that each block or inclosed figure slants from the lower base-line of each cross-depression to the top line of the next lower cross-depression. The line on which Fig. 2 is taken is through the vertical grooves E, so that said view shows the depression or offset of each alternate row of blocks.

25 Each block or figure inclosed by the irregular cross-depressions and intersecting vertical grooves has a central raised figure F of a configuration substantially as shown.

What I claim is—

30 The design for a metallic roofing-plate herein shown and described, consisting of the wave-like depressions or offsets A A, zigzag depressions or offsets B B, escaloped depressions or offsets C C, and triad depressions or offsets D D, all crosswise of the plate, and the vertical grooved depressions E, gradually tapering in depth from the highest point of each cross-depression to the lowest point of the upper adjacent cross-depression, the inclosed figure having a central raised figure F, as set forth.

LONGLEY LEWIS SAGENDORPH.
